UNITED STATES PATENT OFFICE

119,042

DESIGN FOR A CABINET OR THE LIKE

George L. McCarthy, Rye, N. Y., assignor to Eastman Kodak Company, Rochester, N. Y., a corporation of New Jersey

Application May 6, 1939, Serial No. 84,830

Term of patent 14 years

To all whom it may concern:

Be it known that I, George L. McCarthy, a citizen of the United States, residing at Rye, in the county of Westchester and State of New York, have invented a new, original, and ornamental Design for Cabinets or the like, of which the following is a specification, reference being had to the accompanying drawings, forming a part thereof.

In the drawings:

Fig. 1 is a perspective view of a cabinet or the like showing my new design as it appears in the extended position.

Fig. 2 is a top plan view of the cabinet shown in Fig. 1.

Fig. 3 is a view similar to Fig. 1 but with the parts in retracted position.

Fig. 4 is a front elevational view of the cabinet, with the parts in extended position, being broken away for the purposes of better illustration.

While the back of the cabinet is not shown in the drawings, it is perfectly plain and resembles the front view of the cabinet when the parts are in a folded position, as shown in Fig. 3.

I claim:

The ornamental design for a cabinet or the like, as shown and described.

GEORGE L. McCARTHY.
